Filed May 25, 1961, Ser. No. 65,335

Term of patent 7 years

(Cl. D34—11)

FIG. 1

FIG. 2

FIG. 3

The essential feature of my design resides in the loops serving as legs and the central circumferential flange of the leather pig bank as shown in FIGURES 1—4.

I claim:

The ornamental design for a leather pig bank, as shown and described.
